UNITED STATES PATENT OFFICE.

DENNIS BUTLER, OF CUSTER, SOUTH DAKOTA.

DESIGN FOR A RAILROAD-SPIKE.

SPECIFICATION forming part of Design No. 29,189, dated August 9, 1898.

Application filed July 16, 1898. Serial No. 686,160. Term of patent 14 years.

To all whom it may concern:

Be it known that I, DENNIS BUTLER, a citizen of the United States, residing at Custer city, in the county of Custer and State of South Dakota, have invented a new and original Design for Railroad-Spikes, of which the following is a specification.

My invention relates to a new and improved design for railroad-spikes, and is illustrated in the accompanying drawings, in which—

Figure 1 is a side elevation of the railroad-spike, and Fig. 2 is a perspective view.

The leading features of my design consist in a spike having a shank provided with a tapering point, at the upper end of the rear part of which is formed a ledge or shoulder and intermediate the extremities of the shank a similar shoulder, the faces of said shoulders being slightly inclined, while immediately below the head of the spike and at the rear is an extension having a step-like conformation, as shown.

In the said drawings the reference-numeral 1 indicates the shank of the spike, and 2 the head thereof. The lower extremity of the shank is formed into a tapering point 3, at the upper end of the rear part of which is a

ledge or shoulder 4, having a slightly-inclined face 5. At the rear of the shank and intermediate its ends is formed a shoulder or ledge 6, similar to the shoulder 4 and having a similar inclined face 7, the shoulder gradually disappearing and merging into the shank 1, as shown at 8.

At the neck of the spike or immediately below the head 2 and at the rear of the shank is an extension 9, having a step-like conformation, as shown at 10.

My design presents a railroad-spike having a new, distinguishing, and pleasing appearance.

Having described my invention, what I claim as new, and desire to secure by Letters Patent, is—

The design for a railroad-spike herein shown and described.

In testimony whereof I have hereunto set my hand in presence of two subscribing witnesses.

DENNIS BUTLER.
